(57)

CLAIM

The ornamental design for a bench press band, as shown and described.

DESCRIPTION

FIG. 1 is a top, front, right side perspective view of a bench press band, showing my new design;

FIG. 2 is a top plan view thereof;

FIG. 3 is a front elevational view thereof; and,

FIG. 4 is a left side elevational view thereof.

The bottom plan view is omitted due to identical with the top plan view.

The back elevational view is omitted due to identical with the front elevational view.
